(57) **CLAIM**

The ornamental design for a basketball hand-held noise-maker, as shown and described.

DESCRIPTION

FIG. 1 is a front elevational view showing my new design for the basketball hand-held noisemaker with its hemispheres joined, the rear elevational view being a mirror image thereof; FIG. 2 is a top plan view thereof, the bottom view being a mirror image thereof;

FIG. 3 is an elevational view of the concave side of one hemispherical component of the basketball hand-held noise-maker;

FIG. 4 is a left elevational view of FIGS. 1 and 2, the right elevational view being a mirror image thereof;

FIG. 5 is an isometric view showing the design in use; and, FIG. 6 is another front elevational view thereof, showing my design being carried by the user.

The broken lines are included for the purpose of illustrating portions of the noisemaker and its environment that form no part of the claimed design.
